CLAIM

I claim the ornamental design for a mount for an electronic device, as shown and described.

DESCRIPTION

FIG. 1 is a plan view of the top of the mount for an electronic device

FIG. 2. Is an elevation view of the front of the mount for an electronic device

FIG. 3. is an elevation view of left side of the mount for an electronic device

FIG. 4 is an isometric view, from the front right of the mount for an electronic device; and,

FIG. 5 is an isometric view, from the back left of the mount for an electronic device.
